TWO-CYCLE ENGINE AND PUMP

Oscar H. Erickson, Puyallup, Wash.

Application January 12, 1948, Serial No. 1,742

2 Claims. (Cl. 123—70)

1

This invention relates to internal combustion engines and it has reference more particularly to internal combustion engines that operate on a two stroke cycle and wherein each power unit of the engine comprises a power cylinder and a companion pump cylinder, the latter containing a reciprocating piston whereby carbureted fuel charges are caused to be sucked into the cylinder and then forcibly driven into the power cylinder in timing with the reciprocal action of a power piston that is contained in the power cylinder. The present invention has reference particularly to engines of the types described and illustrated in my United States patents issued under Numbers 1,890,148 and 2,294,332, and is an improvement thereon.

It is the principal object of this invention to provide an engine of the above stated kind wherein provision is made for a better control of the flow of gases between the cylinders through an intercommunicating passage which has been referred to as an exchange passage, the timing of the opening of the exchange passage being controlled by sleeve valves that operate respectively in the power and pump cylinders, and which valves have ports that time the admittance of fuel charges into the pump cylinder, their advancement into the power cylinder, and the exhausting of used charges from the engine.

It is also an object of this invention to provide a novel arrangement of ports in the sleeve valves for the control of the flow of gases through the transfer passage that permits of admittance of burned gases from the power cylinder into the pump cylinder for a better volatilizing of fuel and an increase in power therefrom.

Other objects of the invention reside in the advantages to be obtained, by the use of two sleeve valves for the control of gases, over the use of a single sleeve as used in my prior patent.

Still further objects reside in the details of construction of parts and in the mode of operation, as will hereinafter be fully described.

In accomplishing these and other objects of the invention, I have provided the improved details of construction, the preferred forms of which are illustrated in the accompanying drawings, wherein—

Fig. 1 is a side elevation of an engine embodying the improvements of the present invention therein; one power unit being shown in vertical section for better understanding.

Fig. 2 is a horizontal section taken substantially on line 2—2 in Fig. 1.

Figs. 3 to 7, inclusive, are views diagrammatically illustrating the mode of operation of the engine, and the changing relationship of power and pump pistons, and the sleeve valves with the rotation of the crank shaft to which these parts are connected.

2

Fig. 8 is an enlarged, sectional detail showing the unchanging relationship and relative size of passages in the cylinder walls and the relationship of ports of the valve sleeves which move reciprocally across the cylinder ports.

Referring more in detail to the drawings—

In Figs. 1 and 2, I have illustrated, in elevation and section, an engine embodied by the present invention and comprising two power units; 10 each unit including a power cylinder and a pump cylinder. It is to be understood, however, that such an engine might comprise one or more of said units, all delivering power to the same crank shaft, and could be made in various sizes to meet requirements or particular uses. The engine, as here shown, comprises a cylinder block 10 in which there are formed two power cylinders 12—12 and two pump cylinders 13—13. The power cylinders are parallel and located at opposite ends of the block and the pump cylinders are located between the power cylinders, parallel in line therewith and adjacent each other.

It is shown best in Fig. 2 that the cylinder block 10 is formed at one side with a fuel intake port 15, to which a manifold 16 leading from a source of carbureted fuel is connected, and from which port 15, passages 17—17 open laterally into the two pump cylinders.

It is also shown in Fig. 2 that each pump cylinder has a passage 18 therefrom into its companion power cylinder, which passages I have designated as the "transfer passages" and through which passages the fuel charges are forcibly advanced from the pump cylinders into the power cylinders.

Each power cylinder 12 is shown in Fig. 2 as being equipped with exhaust ports 20—20 at opposite sides and, as will be understood by reference to Fig. 1, the exhaust ports are at a slightly lower level than the fuel inlet port 15 of the pump cylinder, and the transfer passage 18 is at a higher level than the inlet port. The relationship of the fuel intake port, the exhaust port and the transfer passage with reference to a horizontal level in each power unit, is best understood by reference to Figs. 3 to 7, wherein, for purpose of better understanding, the intake and exhaust ports have been shown as located in the cylinder walls opposite the transfer passage.

Since all units of the engine are alike in construction and mode of operation, the following description which will be directed to one unit only will be understood to apply equally to all that may be incorporated in an engine.

Reciprocally fitted in the power cylinder 12 is a sleeve valve member 25, and likewise reciprocally fitted in the pump cylinders are sleeve valve members 26. Each sleeve valve member is of substantial length, extending substantially the full length of its cylinder and projecting somewhat below the cylinder block. These sleeves are

coextensive and at their lower ends, see Fig. 1, are formed at adjacent edges with depending lugs 21-27 for attachment to a connecting rod as later explained.

The upper end of cylinder 25 is closed by a head 28 and the cylinder 26 is likewise closed by a head 29. The head 28 mounts a spark plug 30 as in the usual manner for igniting the fuel charges in the cylinder, and this head has a depending portion 28a extended down into the cylinder to limit the explosion chamber volume. Likewise, the head 29 extends down into the pump cylinder 13 to the approximate level of the transfer passage and slightly above the upper limit of travel of the pump piston.

Reciprocally contained in the sleeve 25 of the power cylinder is the power piston 32, and likewise reciprocally contained in the sleeve 26 is a pump piston 33.

Mounted in the central, vertical plane of the cylinders, below the block, is a crank shaft 35, revolvably mounted at its ends in suitable bearings as at 36. This crank shaft, for each unit of the engine, is formed with a crank throw 37 connected by a rod 38 with the wrist pin 39 of power piston 32. Likewise, the crank shaft has a crank throw 40 connected by rod 42 with the wrist pin 43 of pump piston 33. Between the points of connection with rods 38 and 42, the crank shaft is formed with an eccentric journal 44 on which a connecting rod 45 is mounted, and this rod is joined at its upper end with the lugs 21-27 of the sleeve valves 25 and 26 by means of a wrist pin 47.

The lengths of the throws or crank arms 37 and 40 are equal, with the throw 40 exactly ninety degrees in advance of the throw 37. The eccentric 46 is exactly 67½ degrees in advance of crank arm 40 of the pump and is relatively short; the relationship of the several crank arms being best shown diagrammatically in Fig. 7, which shows the crank arm 37 extended horizontally to the left of the crank shaft axis, the arm 40 extending vertically upward from the shaft center and crank arm 44 extending angularly 67½ degrees in advance of arm 40.

The sleeve valve 28 of each pump piston is provided at one side with a port 50 adapted, with the reciprocal action of the sleeve, to move downwardly and upwardly across the corresponding intake port 15. Also, the sleeve valve member 26 is provided, at approximately the same level of port 50, with a port 52 adapted to move upwardly and downwardly across the transfer passage 18 communicating with the companion power cylinder.

The sleeve valve member 25 of each power cylinder, likewise, is provided with a wall port 54 adapted, with the reciprocal action of the sleeve, to move upwardly and downwardly across the transfer port 18, and with a port 55 at a lower level that is adapted to move upwardly and downwardly across the exhaust port 20.

The piston 32 of the pump cylinder has a flat upper end surface as shown. Likewise, the power piston is formed with a flat upper end surface but at one side has an upward extension 60 formed with a passage 61 that moves vertically across the sleeve port 54 with the reciprocal action of the piston 25. The upper end of the extension 60 is cut away at the outside to form an inwardly and upwardly curved deflecting surface 62 for a purpose presently explained.

The several ports and passages of the cylinders and sleeves are all formed with horizontal,

straight cut top and bottom edges so as to provide an instant cut off or opening from one to the other when the ports move across each other. In Fig. 8 the relationship and proportionate vertical dimensions of the ports 15, 18 and 20 of the cylinder walls are shown, and this relationship remains constant. Also, there is shown the relationship and proportionate vertical dimensions of ports 50, 52, 54 and 55 in the sleeve valve members and the location of these ports relative to the cylinder ports at the instant the port 50 of pump sleeve 26 starts to move downwardly into registration with the fuel intake port 15.

For better understanding of operation, it will here be explained that in the present instance the intake port 15 of cylinder 13 has a vertical width of $\frac{3}{8}$ ". Likewise, the sleeve port 50 has a vertical width of $\frac{3}{8}$ ". The sleeve port 52 has a vertical width of $\frac{1}{16}$ " and its lower edge is level with the lower edge of port 50. The transfer passage 18 is $\frac{1}{16}$ " in width vertically, and its bottom edge is $\frac{1}{16}$ " above the level of the bottom edge of the port 15. The ports 54 and 55 in the sleeve 25 are each $\frac{1}{4}$ " in vertical width and port 54 is positioned with its lower edge $\frac{1}{16}$ " above the level of the bottom edge of port 52, and port 55 is located with its top edge $1\frac{3}{8}$ " below the bottom edge of port 54. The ports of the two sleeve valve members maintain a constant relationship to each other but change with respect to the cylinder ports with the reciprocal action of the sleeves as will be understood by reference to Figs. 3 to 7.

As a matter of explanation, it will further be mentioned that in an engine using port dimensions as above noted, the crank arms 40 and 37 are each $2\frac{1}{4}$ " long and the eccentric 46 is offset from the crank shaft axis $\frac{1}{2}$ ".

Assuming the parts to be so constructed and assembled, and the spark plugs connected in a circuit that is properly timed, operation of the unit of the engine is as follows: Starting with the pistons in the relative positions shown in Fig. 3, and assuming the crank shaft to be rotating clockwise, it is understood by reference to the position of the crank arms that the two sleeve valve members 25 and 26 and the pump piston will be moving downwardly and the power piston will be moving upwardly. At the instant the crank arm 40 of the pump piston reaches a position approximately 35° past top dead center, the lower edge of the port 50 of the sleeve in the pump piston uncovers the top edge of the intake port 15. Partial vacuum has already been created in the pump cylinder and as the pump piston continues to move down and port 50 continues to uncover inlet port 15, carbureted fuel is sucked into the pump cylinder. With the rotation of the crank shaft through an additional arc of 155°, the suction stroke of pump piston 33 will have been finished and the eccentric 46 will have moved the sleeves downwardly, causing port 50 first to be registered with port 15 and then moved upwardly out of registration, leaving port 15 closed and bringing the parts to the relative position of Fig. 4. In this position, the pump piston is starting to move upward, sleeve 26 has closed the intake port 15, and the previously intake fuel charge is beginning to be compressed in the pump cylinder. The sleeves are both moving upwardly and the power piston is now moving downwardly.

As the parts move from the position of Fig. 4 toward and into the position of Fig. 5, the port 54 in sleeve 25 has moved upwardly and has

slightly uncovered the transfer port 18 as the top edge of port 52 comes even with the bottom edge of the transfer port. Thus, just prior to the opening of a passage for the delivery of fuel charge from the pump cylinder to the power cylinder, a small portion of burning fuel charge from the power cylinder will have communication through port 54 with the transfer passage 18, admitting burned gas thereinto. Then with the completing of the passage by the port 52 moving into registration with passage 18, the pressure of burning fuel in the power cylinder will force some of this gas back into the pump cylinder to mix with the fuel charge as a means of increasing its effectiveness; this use of gas from the explosion chamber having been explained and its advantages described in my previous patents.

After the first initial blow of gas from the power cylinder into the pump cylinder, the increasing pressure in the pump cylinder reverses the direction and as the rotation of the crank shaft advances the parts from position of Fig. 5 to that of Fig. 6, the upwardly moving pump piston forces the fuel charge through the exchange passage 18, which is uncovered at this time by ports 52 and 54 of the upwardly moving sleeves. As the pump piston moves to its top limit of travel, as in Fig. 7, the power piston still moves upwardly on its compression stroke and sleeves, now moving downwardly, move the ports 52 and 54 below and out of registration with the exchange passage 18, thus to close off the pump cylinder for the immediately following suction stroke of the pump piston, and to close the power cylinder for the continued compression of the intaken charge by the upwardly moving power piston.

As the power piston continues to move upwardly, as from position of Fig. 7 to top position, the charge is compressed and is ignited in proper timing to drive the piston on its down stroke. As the power piston moves downwardly under force of expanding fuel, through positions of Figs. 4 and 5, the two sleeves are being moved upwardly, finally bringing port 55 in sleeve 25 into registration with the exhaust port 20 of the power cylinder, as the power piston 32 moves downwardly below the port 55, thus allowing the burned fuel charge to be exhausted. The exhaustion of the burned charge is forced by the incoming fresh charge which is admitted during the final downward travel of the power piston, as in passing from position of Fig. 5 to position of Fig. 6, by reason of the sleeve ports 52 and 54 being brought into registration with exchange passage 18 as was previously explained.

As the fuel charge is being delivered to the power piston, the baffle extension of the power piston is opposite the port 54 as in Fig. 6, and this operates to deflect the incoming charge to the top of the power cylinder, away from the exhaust port, and to force the burned fuel downwardly to the exhaust port.

The above described cycle as disclosed by the successive views of Figs. 3 to 7 is repeated in rapid succession. Where more than one power unit is used, the crank shaft maintains the timed relationship of parts in the units and between the units.

Having thus described my invention, what I claim as new therein and desire to secure by Letters Patent is:

1. An engine of the character described com-

prising, in combination, a power cylinder and a pump cylinder having an exchange passage, a sleeve reciprocally fitted in the pump cylinder, a pump piston reciprocally contained in said sleeve, 5 a sleeve reciprocally fitted in the power cylinder, a power piston reciprocally fitted in the second mentioned sleeve, a crank shaft to which said pistons are connected for equal reciprocal action with the pump piston substantially in advance of the power piston, an eccentric on the crank shaft whereby said sleeves are reciprocated in unison through a relatively short travel interval; said exchange passage being located approximately at the level of the upper limit of travel of the pump piston and near the lower level of travel of the power piston; said power cylinder having an exhaust port approximately at the level of the lower limit of travel of the power piston; said pump cylinder having a fuel intake port spaced below the level of the exchange passage; said sleeve of the pump cylinder having a port that is moved downwardly into registration with the fuel intake port for intaking fuel and then upwardly to close said port as the pump piston moves through its suction stroke; and a second port therein that is moved upwardly into registration with the exchange passage and then downwardly to close the passage as the pump piston moves upwardly; said sleeve of the power piston having a port therein that is moved upwardly into registration with the exchange passage but slightly in advance of the said second port of the other sleeve as the power piston moves upwardly, and a second port that is moved upwardly and into registration with the exhaust port of the power cylinder as the power piston moves to its lower limit of travel.

2. An engine of the character described comprising, in combination, a power cylinder and a pump cylinder having a connecting exchange passage, a sleeve valve reciprocally contained in said pump cylinder, a piston reciprocally contained in the sleeve valve, a sleeve valve reciprocally fitted in the power cylinder, a power piston reciprocally fitted in the second mentioned sleeve valve, a crank shaft to which said pistons are operatively connected for equal reciprocal action with the pump piston substantially in advance of the power piston, means on the crank shaft for reciprocating the sleeve valves for admittance of fuel charges to the pump cylinder and their delivery through the exchange passage to the power cylinder, and the exhaustion of burned charges from the latter; said sleeve valves being operable to admit burning fuel through the exchange passage during a power stroke of the power piston, into the pump cylinder at the start of the delivery stroke of the piston therein.

OSCAR H. ERICKSON.
